[57] CLAIM

The ornamental design for a serving tray or the like, as
shown and described.

DESCRIPTION

FIG. 1 is a front, top and left side perspective view of a
serving tray or the like showing my new design;

FIG. 2 is a side elevational view; and

FIG. 3 is a rear, bottom and right side perspective view.
The stippled shading in FIG. 1 represents a contrast in
texture on the surface of the serving tray or the like.

FIG.1

FIG.2

FIG.3
